HANDLE STARTER ARRANGEMENT FOR
GAS HAMMERS

Spencer B. Maurer and Howard P. Ebert, Cleveland, Ohio, assignors to Chicago Pneumatic Tool Company, New York, N. Y., a corporation of New Jersey

Original application July 25, 1950, Serial No. 175,742, which is a division of Patent No. 2,533,487, dated December 12, 1950. Divided and this application September 19, 1951, Serial No. 248,076

6 Claims. (Cl. 123—185)

1

This invention relates to a portable internal combustion engine, and more particularly to a starter arrangement for such an engine.

This application is a further division of application Serial No. 175,742, filed July 25, 1950, the latter being a divisional application of application Serial No. 690,654, filed August 15, 1946, now Patent No. 2,533,487 issued on December 12, 1950.

In the illustrative embodiment of the invention a portable internal combustion engine of a two-cycle, single cylinder, air cooled type, is used to power a tie tamper tool, which includes a tamping bar mounted vertically in the lower end of the tool. The engine is mounted directly atop a cast aluminum housing, which forms the main body of the tool, and has a pair of handles located in line with and just above the center of gravity of the tool assembly, to assure a proper balance for easy handling of the tool. One of the handles is operatively connected to a starting gear arrangement, whereby the tool operator may start the engine while holding the tool in operating position; once the engine is thus started, said handle is automatically locked in fixed position to serve, in conjunction with the other handle, as a tool manipulating means. By means of the handle starter arrangement of the invention, the tool can be used more efficiently, i. e., with greater savings of time and improved convenience.

The main object of this invention is the introduction of a novel starting mechanism which will enable the operator to start the operation of the tool by a simple manual thrust.

Another object of the invention is to provide an arrangement of operating handles for the tool which are so disposed in relation to the center of gravity of the tool that the entire device is easily moved from place to place while the mechanism is still in operation.

Another object is the use of a novel latch arranged so that the handle by which the machine is started may be easily released or slammed into a locked position by the operator while the mechanism is in vibratory operation.

Another object of the invention is to provide a member which will have the two-fold function of a handle useful in directing the tool when in operation and of a starter for the engine.

Other objects and structural details of the invention will be apparent from the description when read in conjunction with the accompanying drawings, wherein:

Fig. 1 is a view, in perspective, of the tool of the present invention, shown adapted for the

tamping operations, with the starter handle in the lowered position;

Figs. 2 and 3 are respectively front and side views of the tool in elevation, with the starter handle in the raised or normal position;

Fig. 4 is a longitudinal section taken along the line 4—4 of Fig. 2, the lower part of the tool being shown in elevation;

Fig. 5 is a sectional view of the upper portion of the tool, similar to Fig. 4 but on a larger scale, and showing the engine and transmission and starting mechanism;

Fig. 6 is a side elevation of the upper portion of the starter handle, showing the latch in horizontal position;

Fig. 7 is a view looking downward, showing the latching device in plan, and the starter handle in section, as indicated by the arrows 9 in Fig. 6;

Fig. 8 is a detail view of the latch, in elevation, as viewed from the left of Fig. 6;

Fig. 9 is another elevational view of the latch as seen from the bottom of Fig. 6;

Fig. 10 is a longitudinal sectional view of the transmission mechanism shown in relation to the starter handle and shaft with the intervening clutch in position for starting operation;

Fig. 4 is drawn to a larger scale than Figs. 1, 2 and 3. Fig. 5 is on a larger scale than Fig. 4; while Fig. 10 is further enlarged. Figs. 6, 7, 8 and 9 are the most enlarged, being drawn to twice the scale of Fig. 5.

As shown in Fig. 1, the tool of the invention is a portable, unitary structure which may be manipulated by one or two men by means of properly and conveniently disposed handles 13 and 14. For purposes of description, the tool may be considered as divided into a plurality of cooperating sections or parts including an upper portion 15, a downwardly extending barrel 16, and a barrel extension or nose 17. Extension or nose 17 supports a working implement 18 which, in the present instance, is a tamping bar. The transmission means, hereinafter more fully described, comprises an engine crankshaft 22 driven by the piston 21, a main crankshaft 23 actuated by the engine crankshaft 22 through pinion and gear means, and a connecting rod 24 between the main crankshaft 23 and the cage 20.

The upper portion 15 of the tool contains the internal combustion engine and controls therefore, including the starting mechanism and flywheel magneto. In the illustrative embodiment the engine is of the two-cycle type. The principal supporting element for the engine is a frame piece or crank case 21, to which is bolted

a cover 61^a, the frame piece and cover being made of aluminum, and cooperating to form an air-tight crankcase chamber 62 through which the connecting rod 63 passes. The driving piston 21 reciprocates within a cylinder 64 in the cylinder head 65 secured to the frame in conventional manner. It will be seen that the piston 21 divides the interior of the cylinder 64 in such a way as to separate the upper chamber 66 from the lower chamber 62 which chambers may be respectively identified as the "combustion chamber" and the "pre-compression chamber." A mixture of gasoline and air is introduced into the combustion chamber 66 through a port 67 in the cylinder 64 while burned gases resulting from the explosion within the cylinder will escape through an exhaust port 68. The port 67 communicates with a transfer passage 69 formed in the cylinder head. The flow of gasoline and air into the pre-compression chamber 62 is controlled by a carburetor (not shown).

Transfer passage 69 communicates also with the precompression chamber 62 by a port 70 in the piston, whenever port 70 registers with a complementary cylinder port. The port 67 is controlled by the piston 21 and is open only in the lowermost operative position of the piston, as in Fig. 5. In the operation of the engine an explosive charge, previously introduced into the combustion chamber 66 is ignited by a spark plug 70^a mounted in the cylinder head 65 and extending into chamber 66. The piston 21 is thereby driven downward through its power stroke, and near the end of its downward movement uncovers exhaust port 68. Shortly after the opening of such port, the piston 23 uncovers port 67 and a precompressed mixture of gasoline and air flows into the combustion chamber 66. The mixture is directed upwards by a curved deflecting surface 74 on the head of the piston 21 and forces the burned gases downward and out of the exhaust port. Near the start of the upward or return stroke of the piston the port 67 and exhaust port 68 are closed. As the piston 21 continues its upward movement the precompression chamber 62 expands in size and draws a fresh mixture of air and gas from the carburetor. The fresh gases are prevented from entering the combustion chamber 66 at this time. While a new charge is thus drawn into the precompression chamber 62, the one previously admitted to the chamber 66 is compressed and as the piston reaches its uppermost position is ignited and explodes. The downward movement of the piston resulting from the explosion again reduces the size of the precompression chamber 62 and the gases within the chamber are first compressed and later transferred through the supply passages 69 to the upper chamber 66. The engine thus completes a cycle of operation in two strokes or one reciprocation of the piston; each descent of the piston being a power stroke occasioned by an explosion in the combustion chamber.

Motion is transmitted from the piston 21 through the engine crankshaft 22 to the main shaft 23. The engine crankshaft 22 is rotatably supported in ball bearing assemblies 76 and 77, the latter being mounted in the frame 61. The left hand end of the engine crankshaft (as viewed in Fig. 5) extends into the crankcase chamber 62 and has keyed thereto, as at 78, a crank arm 79. Arm 79 has an outwardly projecting stud 81 extending into a cylindrical aperture 82 in the connecting rod 63 and is also formed with a fan-shaped counterweight 83. Needle bearings 75

80 are provided for the easy rotation of the stud 81 within the connecting rod receiving aperture 82.

For effecting return motion of the piston 21 and thereby of the piston hammer assembly, a fly-wheel 84 is mounted upon the outer end of the engine crankshaft. The kinetic energy stored in the fly-wheel 84 on the power stroke of the piston 21, in conjunction with the counterweight 83, is sufficient to continue the rotation of the crankshaft 22 and to transmit through the crank arm 79 and connecting rod 63 force for the return stroke of the piston 21. The connection between the rod 63 and the crankshaft 22 is such that they are constrained to move in unison, and operation of either element effects a simultaneous operation of the other. Their relationship as driven and driving elements is mutual and reversible.

The ignition system of the tool includes a fly-wheel magneto mechanism for generating an electric current which is supplied through a cable 85 to the spark plug 70^a and is adapted to supply interrupted current under the control of suitable timing or circuit breaking mechanism. The fly-wheel magneto and circuit breaker are combined in a unitary structure which in itself is old and well-known. An embodiment thereof with some modifications not material to the invention is more fully described in Fitch Patent 2,333,419. It need merely be said that in the present construction the permanent magnet 87 is secured to the fly-wheel 84 and acts as the rotor which sets up magnetic lines of force as it revolves around the stationary coil 88, thereby inducing current pulsations which are transmitted through conductor 85. The fly-wheel magnet mechanism is mounted upon the right hand end of the crankshaft 22, being keyed thereto at 89 and retained against longitudinal movement along the shaft by a suitable nut 90 and washer 91. The magneto housing 92, secured to the crank case or frame 61, serves as a support for the ball bearing 76 in which crankshaft 22 is mounted.

The engine crankshaft 22 drives the main crankshaft 23 by means of pinion 93 on the engine crankshaft and the gear wheel 94 which is integral with the main crankshaft. Main crankshaft 23 is rotatably mounted in the frame 61 by needle bearings 96 and ball thrust bearings 97, and is provided at its forward portion with splines which form a pinion 98 to cooperate with the toothed clutch ring 99, as hereinbefore described. The inner face of gear wheel 94 is provided with a stud 101 which projects into the circular aperture 102 in the terminal portion 103 of the cage connecting rod 24, a bushing 104 being disposed between the stud and the rod terminal. Connecting rod 24 is connected at its lower end to the cage 20 by wrist pin 55, as hereinbefore described. It thus may be seen that the reciprocal motion of the engine or driving piston 21 is transmitted through the connecting rod 63 and the crankshaft arm 79 to impart rotary motion to the engine crankshaft 22 and that in operation the engine crankshaft 22 drives the main crankshaft 23. Crankshaft 23, through the cage connecting rod 24, acts as a reciprocating driver for the cage 20.

The toothed clutch ring 99 and rollers 105, as shown in Figs. 5 and 10, cooperate to form a clutch mechanism between the starter shaft 107 and the main crankshaft 23. Ring 99 is formed with an axial bore 108 and with a toothed pe-

periphery 109 to gear with the splined portion of the main crankshaft 23. The inner wall of the ring 99 is provided with an annular recess 111 (Fig. 5) to seat a flanged bearing ring 112, the body of which is brazed to the clutch ring 99 and the flange 113 of which forms a bearing for the ring assembly upon the starter shaft 107. The bearing ring 112 is used only to simplify machining operations in the manufacture of the clutch ring; otherwise said clutch ring and flanged ring can be made unitary. Flange 113 is seated in a felt washer 115. The axial bore 108 of the clutch ring 99 is provided with a plurality of spaced slots 116 (Fig. 10) circumferentially arranged and extending axially from the body of the brazed ring to the outer wall of the clutch ring. Each slot is formed with an adjacent arcuate portion 117 the purpose of which will be explained.

As best shown in Fig. 5, the starter shaft 107 is mounted in the frame 61, its end portions being supported by needle bearings 118 and 119 which are carried respectively by the frame 61 and the starter cover 121. The shaft is formed with a central portion 122 of larger diameter; the outer radial face of which serves as a locating shoulder 123. A washer 124 is disposed between the shoulder 123 and the starter cover 121. The flange 113 of the flange ring 112 abuts against the outer radial wall of the terminal 125 of the starter handle 13, the inner wall 126 of said handle abutting against the frame 61. In this manner the frame maintains the starter shaft 107 against axial movement inwardly and the starter cover 121 maintains it against axial movement outwardly.

The periphery of the central portion 122 of the starter shaft 107 is formed with a plurality of longitudinally extending spaced grooves 129 which serve, in conjunction with the cooperating slots 116 in the bore of the clutch ring 99, as seats for rollers 106 to form a clutch as previously stated. Each peripheral groove has an arcuate portion 130 throughout its length which has the same radius as a roller and forms a shoulder adapted to engage a roller to force it against the arcuate portion 117 of the slot 116 when shaft 107 is rotated counterclockwise (as viewed in Fig. 10) by the rotary thrust of the starter handle 13. One of the rollers 106, which will be at rest upon the upper portion of the starter shaft when the tool is not in operation, will wedge between a shoulder 130 of the starter shaft 107 and an arcuate portion 117 of a slot 116 when the shaft is actuated. In Fig. 9 such engagement is shown in the "10 o'clock position," although in actual operations such engagement or clutching may take place at any point in the upper portion of the shaft. Clutching will not be effected in the lower regions since the rollers will drop by gravity into the slots 116 when the tool is at rest. Motion is imparted to the starter shaft by a sudden downward thrust by the operator of the starter arm 13 whose inner terminal 125 is provided with teeth 132 to engage splines 133 formed on the forward portion of the starter shaft 107. Such starting motion of the starter shaft is counterclockwise and the clutch ring 99 moves in the same direction at the speed of the starter shaft. Said clutch ring transmits motion at a higher speed to the main crankshaft, thence at a still higher speed to the engine or magneto crankshaft 22. As the engine picks up speed, the clutch ring will overrun the starter shaft and the rollers will be urged by centrifugal force into the slots 116 where they

will remain throughout the normal operation of the tool.

In the illustrative embodiment the total gear ratio from the starter shaft 107 to the engine crankshaft 22 is 11.4 to 1. Thus a quarter turn of the starter shaft will turn the engine over approximately three times. A rapid downward thrust of the starter handle 13 through its normal ten inch stroke (approximately one-quarter turn of starter shaft) will produce more than three full revolutions of the engine at a fairly high speed.

The gear ratio between the engine crankshaft 22 and the main crankshaft 23 is about 2.85 to 1. The advantages of using a high speed motor with gear reduction are more power per cubic inch of motor, more cooling air with a smaller fan, better magneto operation (hotter spark) and smoother operation due to larger number of smaller motor impulses and accentuated flywheel effect of the rather heavy magneto rotor.

When the tool is not in operation (Figs. 2 and 3) the starter handle 13 is maintained in locked position against one side of the tool by the latching mechanism 134, best shown in Figs. 6, 7, 8 and 9. When the tool is in operation, the starter handle is clear of the latching mechanism, as in Fig. 1. Latching mechanism 134 comprises a stud 135 screwed into the frame 61, a latch 136 which is pivotally mounted on the outer end of the stud and is provided with a handle 137, a helical spring 138 mounted upon the stud to urge the latch outward, a nut 139 preventing outward movement of the latch, and a cotter pin 140 to secure the nut on the stud 135. The spring is formed with an extending terminal 141 which is in pressing engagement with the frame 61 at 142 (Figs. 1 and 2) and with an extending terminal 143 (Figs. 6 and 7) at its other end which engages projecting arm 144 of the latch. In the normal position of the latch the spring urges the latch in a counterclockwise direction so that the arm 144 (Fig. 7) rests in a depression 145 (Fig. 7) in the housing, the handle of the latch pointing downwardly and to the left as shown in Figs. 1 and 3. When the operator shuts off the motor and desires to lay the tool aside, as is frequently required under working conditions on the railroad tracks, he slams the starter handle upwardly and inwardly. The cross bar 146, in the area indicated at 147, then strikes the outer end 148 of the latch handle 137 camming it upwardly and clockwise against the resistance of the helical torsion spring 138. As the upward and clockwise motion of the cross bar continues, the bar in the area indicated at 149 (Fig. 6) strikes the projection 151 of the latch causing a further camming action upwardly until the cross bar finally clears the latch which then is sprung downwardly in a counterclockwise direction until its movement is arrested by the projecting arm 144 falling into the depression 145 of the housing. The handle is thus quickly locked into a position which is inoperative for starting purposes but operative in the sense of enabling the manipulation of the machine during tamping operations. It is not necessary for the operator to transfer his grip from the starting handle after starting the machine since this handle is also used for manipulating the unit. To unlock the latch, it is merely necessary for the operator by manipulative pressure to lift the latch in a clockwise direction, slightly beyond the horizontal position shown in Fig. 6 and move the starter handle 13 outwardly in a clockwise

direction to the position shown in Fig. 1. He then by a quick thrust of the starter handle can start the motor. A locating pin 152 projecting from the frame 61 cooperates with a recess 153 in the cross bar of the starter handle to maintain the handle in rigid position when locked, so as to minimize damage from accidental blows to which the tool is subjected under ordinary working conditions.

What is claimed is:

1. In a portable internal combustion engine, a starter arrangement comprising a manipulable member pivotally mounted at one end to the engine structure and having a handle at the other end, means to latch the manipulable member in stable position so that the handle may be used for positional maintenance of the engine, a transmission means associated with the main crank-shaft of the engine, and an overrunning clutch means coupling the manipulable member to the transmission means when said member is moved in one direction about its pivot.

2. In a portable internal combustion engine, a starter arrangement according to claim 1 wherein the overrunning clutch means is comprised of a starter shaft formed with a plurality of axial grooves in its periphery, each groove having a leading sloped portion and a trailing arcuate portion, a driven member forming part of the transmission means and having a bore provided with a plurality of axial slots, each slot having a leading wall formed with an internally and rearwardly facing arcuate portion of the same radius of that of the arcuate portion of said groove, and a plurality of rollers disposed between the starter

10

15

20

25

30

35

shaft grooves and the slots of the driven member, each of said rollers having a radius equal to that of the arcuate portions.

3. In a portable internal combustion engine, a starter arrangement according to claim 2, wherein the pivoted end of the manipulable member is securely affixed to the starter shaft.

4. In a portable internal combustion engine, a starter arrangement according to claim 3 wherein

one or more of the rollers are adapted to engage the arcuate portions of the starter shaft and the driven member when the manipulable member is moved in one direction about its pivot, and to disengage said arcuate portions and rest in the slots of the driven member, as a result of centrifugal force, when the driven member overruns the starter shaft.

5. In a portable internal combustion engine, a starter arrangement according to claim 4, wherein the number of grooves formed in the starter shaft exceeds the number of slots in the driven member.

6. In a portable internal combustion engine, a starter arrangement according to claim 5, wherein the transmission ratio between the starter shaft and the main crankshaft of the engine is about 11.4 to 1.
